UNITED STATES PATENT OFFICE.

RALPH E. HIGGS, OF DALLAS, TEXAS.

CLEANING INSTRUMENT FOR MATRICES IN TYPESETTING MACHINES.

Application filed December 13, 1924. Serial No. 755,622.

To all whom it may concern:

Be it known that I, RALPH E. HIGGS, a citizen of the United States, residing at Dallas, in the county of Dallas and State 5 of Texas, have invented certain new and useful Improvements in Cleaning Instruments for Matrices in Typesetting Machines, of which the following is a specification.

This invention has relation to type cleaning instruments and it relates more specifically to a device for cleaning the matrices in a type setting apparatus such as the lino-type or similar machine.

In order that the invention may be clearly understood it may be stated briefly that in all machines for setting type there is a set of small, flat, rectangular pieces of metal known as matrices, some 780 in number comprising a set. Each matrix must be kept 10 clean so that the operator can maintain a maximum rate of speed on the machine. This he cannot do when the matrices become dirty. As those skilled in the printing art are aware, gasoline or similar liquids 15 cannot be advantageously used to clean a matrix, as this causes them to deteriorate, permitting the ink to cause hair-lines on the printed matter.

The object of the invention is to provide 20 an instrument which will clean these matrices without the use of gasoline or injurious liquids and so shaped as to rub and clean away the dirt.

Another object of the invention is that 25 the cleaning instrument is so shaped that it will approximately fit between the "ears" and upon the edges of a matrix to remove the dirt.

The rub mat or instrument comprising 30 the invention is also formed of one piece of material and has no complicated parts, hence may be manufactured economically.

With these and other minor yet important advantages in view, the invention 35 will be more clearly understood from a perusal of the following description, taken in connection with the accompanying drawings, wherein:

Figure 1 is a perspective view of the invention illustrating its position when used 40 in cleaning a galley of matrices.

Figure 2 is a side view of the instrument; and

Figure 3 is a cross-sectional view thereof.

Referring to the drawings more in detail, 55 the instrument or rub mat is molded of one piece of rubber of relatively oblong shape on top and has a handle 1. This handle, however, may be affixed separately, if preferred.

By reference to Figure 1 it will be noticed that the bottom of the rub mat or instrument is rocker-shaped and has a ridge 3 extending below the main body 3^a. The ends 4—4 are bevelled as shown in the drawing so as to permit them to ride over and upon the "ears" 5—5 of a matrix 6, a number of which are cleaned at one time, being placed edge up in a tray or galley 7. One of these ears 8 is wider or larger than the 60 one on the opposite side of the matrix and the ridge 2 is therefore placed just off the longitudinal center line of the bottom portion 4^a to enable the ridge to travel between the ears and at the same time permit the 65 ends 4 to slide over and rub off the dirt, etc., and clean the ears. The curved bottom of the ridge cleans and rubs the edge of the matrix between the ears. After one 70 side of the matrices are cleaned they are 75 reversed by simply turning over a plurality of them at a time for cleaning the other side.

It should be understood that the rub mat or instrument is not restricted to any particular material or specific shape and may 80 be made of any material suitable for the 85 purpose.

What is claimed is:

A matrix cleaner formed of solid rubber comprising a rectangular body portion 90 having the opposite ends of its lower face bevelled, a longitudinally extending rib projecting from the lower face of said body portion and positioned intermediate of said bevelled ends, said rib having a convex lower face extending in contiguous alignment with said bevelled ends, the lower face of said body portion at one side of said rib being of greater width than at the opposite side of said rib, and a handle formed with 95 the upper face of said body portion.

In testimony whereof I have signed my name to this specification.

RALPH E. HIGGS.
